CLAIM

We claim the ornamental design for a computer with display,
as shown and described.

DESCRIPTION

FIG. 1 is a perspective view from the front and one side of
a computer with display showing our new design; and,
FIG. 2 is a perspective view from the rear and reverse side
thereof.

The undisclosed bottom view and the surfaces which have
not been completely shown in FIGS. 1 and 2 are understood
not to be a part of the claimed design.
